UNITED STATES PATENT OFFICE.

HARRY L. BRADLEY, OF MILWAUKEE, WISCONSIN.

ELECTRIC SWITCH.

1,266,548.

Specification of Letters Patent.

Patented May 21, 1918.

Application filed May 22, 1918. Serial No. 99,086.

To all whom it may concern:

Be it known that I, HARRY L. BRADLEY, a citizen of the United States, residing at Milwaukee, county of Milwaukee, and State 5 of Wisconsin, have invented certain new and useful Improvements in Electric Switches, of which the following is a specification, reference being had to the accompanying drawings, forming a part thereof.

10 My invention relates to improvements in electric switches, particularly that type which is operated magnetically.

The usual magnetic switch or contactor employs a magnet or solenoid by which a 15 movable arm, carrying one of the contacts of the switch, is moved to make contact with the second contact when the magnet is energized. Upon the deenergization of this magnet, the switch falls open either by

20 gravity or by the action of a spring or a combination of both. The separation of the contacts when the switch falls open is not usually sufficient to disrupt the arc unless assisted by some auxiliary means. This aux-

25 illiary means is generally in the form of what is termed a "magnetic blowout," which consists of an electromagnet with pole pieces so arranged that the path of the lines of force will pass at right angles

30 through the path of the arc. The mechanism of these magnetic blowouts which are generally used on magnetically operated switches, can be described as consisting of a coil provided with projecting pole pieces,

35 which are shielded from contact with the arc by deflectors of some refractory insulating material. These arc shields or deflectors are in such shape as to form substantially a flue or chute through which the

40 heated gases of the arc are drawn.

As the formation of an arc must result in a certain amount of destruction of the contacts, leaving a residuum of oxids and other products of heat and combustion, which are

45 of low conductivity, it is therefore quite essential that the contacts be scraped or filed clean from time to time in order to insure sufficiently high conductivity at the points of contact.

50 In order to facilitate the cleaning of these contact points, it is the practice either to make the arc chute and pole pieces removable from the switch proper or to hinge them in such a manner that they may be

55 moved away from their normal location, thus leaving the contacts exposed for in-

spection and repair. This moving of the pole pieces and arc chute away from the contacts, with the resultant shifting of the magnetic field to a point remote from the 60 path of the arc, leaves the switch subject to the danger of being operated with the magnetic blowout in an inoperative position. This can be readily brought about through accident or carelessness, the result being the 65 destruction of the switch contacts through the continuation of the arc, and not infrequently great damage occurs to the apparatus to which the switch was connected and which it was intended to govern. 70

It is also important that the switch be made as light and compact as possible, that the mass of the various parts be reduced to a minimum, which tends also to reduce the inertia, both mechanically and magnetically, 75 and results in a maximum speed and sensitivity of operation with a low current flow in the magnetizing coil, which is a very desirable characteristic. It is also an advantage to have the switch occupy as little 80 space as is possible in view of the fact that switches are frequently assembled with other apparatus on switch boards and panels, the dimensions of which are often arbitrarily restricted. 85

The coil that furnishes the motive power for the operation of the switch, together with its magnetic circuit, are factors that must be given careful consideration. It is essential that leakage or that part of the 90 total magnetic flux that is diverted from its field of usefulness be as small as possible and the path of the magnetic circuit must be as short as the mechanism will permit and of such dimension as to possess a minimum 95 reluctance, for all waste of the magnetic flux must be offset by making the coil large and powerful enough to compensate for the losses.

The objects of my invention are, first, to 100 provide a means for preventing the switch from being operated when the magnetic blowout mechanism is not in proper position; second, to provide a means by which the switch contacts can be made readily accessible for inspection and cleaning; third, to reduce the leakage or diversion of the flux from the operating coil to a smaller amount than has heretofore been the case in switches of this type. 105

To further describe my invention, I refer 110 to the following drawings in which,

2

Figure 1 is a front elevation of a switch embodying my invention, Figs. 2 and 3, a front and side elevation, showing the switch with the magnetic blowout coil raised and the contacts widely separated for inspection, in Fig. 3 part of the blowout chute being broken away parts being shown in section. In Fig. 4 the switch is represented in its normally open position with the blowout chute and operating coil partly broken away parts being shown in section. The normally closed position of arm and contact is indicated by dotted lines. Fig. 5 shows the side elevation of a modified form of my device, and Fig. 6 shows the section thereof on the line 6—6 looking in the direction of the arrows.

In these figures, a magnetic frame 1 is mounted upon a suitable insulating support 2. This frame carries a projection 3, which forms the core of the magnet on which is mounted the magnetizing coil 4. Pivoted to the frame 1, by means of the pin 5, is the movable member 6, which is also of magnetic material. This arm carries projecting ears 7 at its lower portion, which pass between the tongues of frame 1 and act as bearings for the pin 5. The upper portion of the arm 6 carries projecting ears 6' in which the pivot 14 is journaled. Pivot 14 attaches the U shaped piece 8 to the upper extremity of this movable arm. The U shaped piece 8 is held in its position against the stop 9 by the spring 10, the contact 11 is secured to the transverse portion of the U shaped member 8 and when the switch is closed is yieldingly held against the fixed contact 12 by the spring 10 which yieldingly engages the member 8. The pivoting of the movable member 6 by the pivot 5 and the member 8 by the pivot 14 forms a two part movable contact carrying member which causes the contact 11 carried thereby to have a yielding rolling contact with the fixed contact 12 when brought into engagement therewith which is desirable as maintaining the contacts in good condition. This contact holder 13 is suitably mounted upon the insulating support 2.

On the movable member 6 is mounted the conical magnetic piece 15 that telescopes with the coil 4 and coil supporting projection 3. This telescoping of the conical piece 15 into the coil 4 is for the purpose of locating the magnetic air gap at a point consistent with the form of construction, where the magnetic leakage will be at a minimum. To the contact holder 13 is fastened a bracket piece 16 that supports the blowout coil 16' and chute 17. The pole pieces 18 and the attached insulating pieces 19 and 20 that go to form the blowout chute surrounding the contacts 11 and 12 are collectively pivoted at 22 to the core 21 of the blowout chute 17 in such a manner that the chute

can be moved upward away from the region of the contacts, as shown in Fig. 3, thus leaving them exposed for inspection.

Attached to the backing plate 2 is a stop 17' against which the movable chute 17 strikes when open from its operative position. This stop 17' projects sufficiently from the backing plate 2 so that the said chute 17 cannot be opened so far that it will not return to its operative position by the force of gravity. 75 If desired said stop may be, as in the drawing, combined with a binding post or the chute may be so designed that a portion thereof will come in contact with the said backing plate before it is lifted so far that 80 it will not return to its operative position by the force of gravity without the use of springs or other actuating mechanism. Because of this construction the chute is always in operative position except when held 85 up by the operator for cleaning the contacts.

To this blowout chute 17 is attached a motion limiting stop 24 insulated from said chute by a bushing 24' for limiting the motion of the contact 11 and attached movable 90 arm 6. This stop is provided with a set screw 23 for adjusting this motion limiting function. The lifting of the blowout chute and the attached motion limiting stop away from the region of the contacts permits the 95 movable arm 6 and attached contact to drop to a position entirely out of the effective field of the coil 4 as shown in Fig. 3, which effectively prevents the switch being operated when opened for cleaning the contacts. It 100 is apparent that if the blowout chute 17 be lifted and the movable arm 6 be dropped for cleaning, and the operator through inadvertence release the blowout chute 17 so that it drops into position before returning the 105 movable arm 6 to its normal position, the conical magnetic piece 15 will be so far from the magnetic coil 4 so as to be unaffected by the magnetic flux thereof, and consequently the switch will not operate. By this means 110 it is impossible to have the switch in operative position unless the blowout chute 17 is in its normal position and incloses the fixed contact and the movable contact piece 11.

By turning the set screw 23 the air gap between the conical magnetic piece 15 and the coil 4 can be regulated so that the switch will operate at a predetermined voltage. If desired the same means may be accomplished 115 by putting a resistance in circuit with the coil 4 so that the desired result of having the coil operate on a predetermined voltage may thus be obtained.

Fig. 5 shows a modified form of my device 125 in which the movable contact 11 is made so long that the ends thereof farthest from the backing plate 2 will not be cleared by the motion limiting stop 24, so that the blowout chute 17 cannot be lifted from its operative 130

position and the movable contact 11 dropped in the position shown in Fig. 3 by accident when said apparatus is assembled for using. In this modified form of my device it is impossible to bring the movable member 6 into the position shown in Fig. 3 by inadvertence or accident. I provide means however for permitting the apparatus to be opened for cleaning and inspection, consisting of a screw 25 against which the stop end 26 of the member 6 rests when the apparatus is assembled for using. When this screw 25 is removed the spring 10 forces the member 6 into the position shown by dotted lines in Fig. 5, thus retracting the end of the movable contact 11 so that it is cleared by the motion limiting stop 24, permitting the apparatus to be opened for inspection and cleaning. If it is desired the same means can be accomplished by so locating the movable stop 24 and the set screw 23 that the said set screw will not clear the end of the movable contact 11 without being unscrewed. I, however, prefer the other form of my device as it is unnecessary to disarrange the adjustment of the set screw 23 in order to enable the device to be opened.

It is apparent from what has been said that there may be two circuits of electricity flowing through my improved switch, the main or motor circuit coming in through the binding post 17', through the coil 16' to the contact 12, through the contact 11, the flexible wire 27, and the binding post 28, and then out to the main line. The auxiliary circuit passes through the binding post 29 to the coil 4 and out through the binding post 30, and is so designed that the switch may be controlled from a remote point.

40 I claim:—

1. In an electric switch the combination of a movable member carrying a contact, a contact engaged by a contact on said member when said member is actuated in one direction, movable means for breaking the arc between said contacts, and a stop operated by said means limiting the movement of said contact carrying member in the opposite direction.

50 2. In an electric switch the combination of a movable member carrying a contact, a contact engaged by a contact on said member when said member is actuated in one direction, movable means for breaking the arc between said contacts, said means automatically returning to and remaining in its operative position, and a stop operated thereby

and limiting the movement of said contact contact carrying member in the opposite direction.

3. In an electric switch the combination of a movable member carrying a contact, a contact engaged by a contact on said member when said member is actuated in one direction, a movable chute or cell surrounding said contacts, and a stop operated by said chute and limiting the movement of said contact carrying member in the opposite direction.

4. In an electric switch the combination of a movable member carrying a contact, a contact engaged by a contact on said member when said member is actuated in one direction, a movable chute or cell surrounding said contacts which automatically returns to and remains in its operative position, and a stop operated by said chute and limiting the movement of said contact carrying member in the opposite direction.

5. In an electric switch the combination of a movable member carrying a contact, a contact engaged by a contact on said member when said member is actuated in one direction, a movable chute or cell surrounding said contacts, and a stop attached to said chute and limiting the movement of said contact carrying member in the opposite direction.

6. In an electric switch the combination of a movable member carrying a contact, a contact engaged by a contact on said member when said member is actuated in one direction, a movable chute or cell surrounding said contacts which automatically returns to and remains in its operative position, and a stop attached to said chute and limiting the movement of said contact carrying member in the opposite direction.

7. In an electric switch the combination of a movable member carrying a contact, a contact engaged by a contact on said member when said member is actuated in one direction, movable means for magnetically breaking the arc between said contacts, a stop operated by said means limiting the movement of said contact carrying member in the opposite direction, and means for preventing the accidental removal of said means for magnetically breaking the arc between said contacts from its operative position.
